WILLIAM M. WELLING, OF BROOKLYN, NEW YORK

RECEPTACLE

Application filed April 18, 1929. Serial No. 356,186.

The present invention relates to new and useful improvements in receptacles, and in its present illustration it is shown as comprising a case for time keeping instruments such for example as watches. It will, however, be obvious that it is equally capable of use in other connections, and it is, therefore, not to be limited to this specific use.

It is one of the objects of the invention to provide a receptacle of the above described type which will be securely held in its closed position and yet at the same time may be opened with a minimum amount of effort.

In fact a receptacle constructed in accordance with the invention can be manipulated with but one hand.

It is a further object of the invention to provide a receptacle which will completely enclose a watch movement in such a manner that the same will be absolutely protected from dirt, dust or foreign matter.

With these and other objects in view, the invention consists in the novel and improved constructions, combinations and arrangements of parts hereinafter described and particularly pointed out in the claims, the advantages of which will be readily understood and appreciated by those skilled in the art.

The invention will be clearly understood from the accompanying drawing illustrating the invention in its preferred forms and the following detailed description of the construction therein shown.

Figure 1 is a view in elevation of the watch case in its closed position,

Figure 2 is a rear view of the watch case in its open position,

Figure 3 is a sectional view showing the position of the parts with the case in its closed position,

Figure 4 is a transverse sectional view taken on the line 4-4 of Figure 3,

Figure 5 is a similar view taken on the line 5-5 of Figure 3,

Figure 6 is a longitudinal sectional view on an enlarged scale showing the parts in the position which they occupy with the case in its open position,

Figure 7 is a similar view taken on the line 7-7 of Figure 6,

Figure 8 is a detail view of a slightly modi-

fied form of latch, the latch being shown in its holding position, and

Figure 9 is a similar view showing the latch in its released position.

Referring specifically to the drawing, the case comprises two half sections 10 and 12 preferably of rectangular form, and adapted and constructed in such manner that when they are closed they form a tight casing. Each of these members 10 and 12 is provided in its edge walls with grooves 14, the purpose of which will be hereinafter specifically described.

The grooves 14 form sliding guides for a watch movement carrying frame 16, the watch movement being designated by the reference numeral 18. The watch movement carrying frame 16 preferably consists of two plates 20 and 22, each formed with a watch movement receiving opening defined by an outwardly extending flange 24 and 26 respectively. The watch movement is designated by the reference numeral 18 and is retained in the flanged openings of the plates 20 and 22 by means of screws 30 in substantially the same manner that watch movements are held in watch cases.

The two plates 20 and 22 which form the watch movement carrying frame are secured together in the position shown, in any desirable manner and have their end edges flared outwardly as at 32 in such a manner as to form abutments or the like on the ends of the watch movement carrying frame. These plates 20 and 22 are of such a width that they extend completely across the half sections 10 and 12 of the casing and into the grooves 14 which grooves form guides in which the watch movement carrying frame slides.

Interposed between each end of the watch movement carrying frame, and the closed end of its respective half casing member, there is a spring 40, and these springs 40 are secured to their respective end of the watch case carrying frame as at 42 with its free end in engagement with the closed end of its respective half casing member as at 44. It is the function of these springs 40 to normally project the half sections 10 and 12 to open position. Movement of the half casing sections

to their open position is limited in that form of the invention shown in Figures 1 to 7 by a suitable latch member which also serves to hold the half sections together to form the closed watch case, which feature of the invention will now be described.

The latch comprises a substantially rectangular plate 50 having two L-shaped slots 52, so arranged in the plate that the short leg 10 54 of each slot extends transversely of the plate 50 and the long leg 56 of the slot extends longitudinally of the plate as shown in Figures 2, 3 and 6. The half sections 10 and 12 each carry a pin 58 and 60 respectively and 15 each of these pins occupies a position in one of the L-shaped slots 52 as more clearly shown in Figures 3 and 6, they being in position at the ends of the short legs of the slots when the case is closed and at the ends of the 20 long legs of the slots when the case is open. These positions of the pins in the slots are shown in Figures 3 and 6 respectively. When the pins are in the short legs of the slots as shown in Figure 3, they are retained in position by the tension of the springs 40 which in 25 the closed position of the case sections are under compression. When the pins occupy the position in the slots in which they are shown in Figure 6, it will be obvious that they 30 serve to limit the movement of the case sections to open position and thus determine the extent to which the case sections open.

The device may be assembled by inserting the ends of the frame 16, into their respective 35 casing members, after which the plate 50 may be positioned in parallel relation with said frame. The pins 58 and 60, are next inserted in openings provided in the casing members and secured therein, preferably by 40 soldering, with their inner free ends projecting into their respective L-shaped slot 52. This sequence of assembly must not necessarily be adhered to, except that one of the pins 58 or 60, will be the last element to be 45 assembled.

The device operates as follows:—

If the device in the closed position as shown in Figure 1, is inverted, that is to say positioned with the monogram plate 70 in the upper left hand corner as shown in Figure 2, upon slight pressure upon the ends of the casing sufficient to relieve the pins of the tension of the springs 40, the latch plate 50 will drop by gravity until the pins 58 and 60 occupy a 50 position at the juncture of the short and long legs of the slots 52. If now the pressure upon the ends of the casing be released, the casing sections will move outwardly under the influence of the springs 40, the pins 58 and 60 travelling through the long legs of the slots 52 and upon reaching the ends thereof further movement of the casing sections is prevented. Stops 32 in the form of projections or lugs extending from the upper wall of the 55 60 casing sections 10 and 12, may also be pro-

vided to limit the separating movement of the casing sections. To close the case, it is only necessary to turn the same over so that the monogram plate 70 is in the lower left hand corner and exert slight pressure upon the ends 70 of the casing sections. This action places the springs under compression and causes the pins to travel along the long legs of the slots 52 until they reach the inner ends thereof. When the pins reach this point in the slots 75 52, the latch plate 50 moves by gravity to the position shown in Figures 1 and 3 and upon release of pressure, the tension of the springs 40 holds the case sections closed.

In Figures 8 and 9 there is shown a slightly 80 modified form of the invention. In this form of the invention, the gravity operated latch comprises a pivoted member 60' pivotally mounted at 61. One end of this member 60' is formed with a hook 62, the opposite end 85 thereof being weighted as at 63.

The two half casings 10 and 12, and the watch carrying frame 16 are of substantially the same construction in this form of the invention as in the preferred form heretofore 90 described except as to those details which are necessary for the proper operation of the latch.

In this last described form of the invention, one of the half casing sections, for example 95 the half casing section 10 is provided with a pin 64 which is adapted for engagement by the hooked end 62 of the latch member 60' as shown in Figure 8.

This form of the invention operates as follows:—

With the parts in the position shown in Figure 8, it is only necessary to invert the device to the position shown in Figure 9 when slight pressure upon the ends will cause 100 the latch member to move to the position in which it is shown in Figure 9 under the influence of its weighted end 63. Upon release of the pressure, the two half sections 105 will move to position where they expose the 110 watch case carrying frame and the watch carried thereby. To close the case, it is only necessary to move the half casing together and again invert the device to the position in which they are shown in Figure 8, in which 115 position the pivoted member moves under the influence of its weighted end 63 to position where its hooked end 62 engages around the pin 64 as shown in said Figure 8. The several parts are held in this position by 120 means of the springs 40 until the device is again inverted and a slight pressure applied to the ends thereof.

While the invention has been illustrated in its preferred forms, it is to be understood 125 that it is not to be limited to the forms in which it is herein illustrated, but may be practiced in various other forms which fall within the purview of the appended claims.

What is claimed as new is:—

1. As an article of manufacture, a supporting frame, a two part casing slidably mounted on said frame and adapted when closed to enclose said frame and when open to expose the same, resilient means interposed between the ends of the frame and the parts of the casing to move said parts to open position, and means for limiting the movement of the parts to open position, and
5 for holding said parts in their closed position, said means being retained in its holding position by the said resilient means.

2. As an article of manufacture, a supporting frame, a two part casing slidably mounted on said frame and adapted when closed to enclose said frame and when open to expose the same, resilient means interposed between the ends of the frame and the parts of the casing to move said parts to open
15 position, means for limiting the movement of the parts to open position, and for holding said parts in their closed position, said means being gravity operated to both its holding and releasing positions and being retained in its holding position by the action
20 of said resilient means.

3. In a device of the character described, a supporting frame, a two part casing slidably mounted upon said frame, means interposed
30 between each end of the frame and its respective casing to move the same relative to the frame, and means for limiting the movement of said members under the influence of said moving means, and for holding said members in their closed position, said last mentioned means comprising a gravity operated latch bridging the supporting frame and carried by the members of the two-part casing.

4. In a device of the character described,
40 a supporting frame, a two part casing slidably mounted upon said frame, means interposed between each end of the frame and its respective casing to move the same relative to the frame, and means for limiting the movement of said members under the influence of said moving means, and for holding said members in their closed position, which is held in its operative position by the action of the moving means of said casing
45 50 sections.

WILLIAM M. WELLING.
